M. SIEVEKING

FIXED RADIOCOUPLER

Filed Oct. 4, 1926

Inventor
M. Sieveling
By his Attorney Wm. H. Reid.

UNITED STATES PATENT OFFICE.

MARTINUS SIEVEKING, OF NEW YORK, N. Y.

FIXED RADIOCOUPLER.

Application filed October 4, 1926. Serial No. 139,327.

This invention has reference to an inductance device used in radio receiving apparatus for producing a regenerative or feedback effect, and relates particularly to a device known as a coupler in a receiving circuit.

The main object of the present invention is to provide a combination of this character that will cause the regenerative effect without distortion or other injurious effects, and which will be non-radiating and also very selective, and which makes the circuit super-regenerative and of increased volume without distortion.

15 A further object of the invention is to provide an inductance device of this character in which the desired effects are produced by a fixed coupler. The tickler coil is provided with the usual taps and switch to divide the wave band. The tuning is done by 20 the variable condenser.

In the accompanying drawing showing one embodiment of my invention,

Figure 1 is a perspective view of the 25 device.

Fig. 2 shows in perspective the frame partly broken away to show the interior.

Fig. 3 is a transverse section.

30 Fig. 4 is a diagram showing the conventional circuit in which the fixed coupler is included in a three coil circuit.

Fig. 5 shows a switch.

In my invention I wind a coil preferably somewhat in the form of an ellipse or zone 35 to constitute the tickler coil. I wind a second coil also preferably in the general form of an ellipse or zone, but which is placed at a right angle to the tickler coil, and which crosses the tickler coil at two opposite places, 40 it being understood that both coils are of a single layer of insulated wire, such as enameled wire. These coils are interlocked and form a single fixed unit. This arrangement is preferably wound over a form such as set 45 forth in Fig. 2, of the drawing, separately, and comprises two somewhat elliptical bands or zones arranged at a right angle and closely wound. The tickler coil is wound first, and the secondary coil is wound over the tickler coil and crosses the latter at a right angle at two opposite places. The two single layers of wire are in contact, but the insulation obviously prevents current passing from one to the other; this close proximity 55 causes the great amount of induction.

This arrangement is preferably wound over a form such as set forth in Fig. 2 separately, and comprises two cylindrical bands or zones arranged at a right angle with flat portions at their two opposite intersections 60 closely wound. As shown I provide two square blocks or plates 3 and 4. I also provide two half cylinder portions 5 and 6 that extend at their ends inside of the plates and each end is secured thereto by bolts 7. I 65 also provide two similar plates 8 and 9 that are practically half cylinders, each provided with a tongue 10 at each end. These tongues are placed against the inner wall of the plates 3 and 4 and locked between the 70 ends of the curved plates 5 and 6, and are secured by suitable bolts 11 at each tongue portion.

This frame will have a tickler coil 12 wound on the outside of one of these cylinder forms, which wires will pass over the opposite plates 3 and 4, and will be in close contact at such portions. This coil is provided with taps 13, 14, 15, and 16 adjacent one terminal 17, so that the circuit between 80 the other terminal 18 and this terminal will vary the effect of this coil. These terminal 13—17 are connected with a suitable switch and thus the effective length of the coil can be varied. This coil is of suitable insulated 85 wire such as enamel coated.

On the other cylindrical form I wind a coil 20, that will cross the coil 12, at the two plates 3 and 4, such wire being insulated, and they are brought in close contact at the 90 two intersections on the flat plates. This coil 20 is shown with terminals 21 and 22. On this coil as a secondary, I wind a suitable primary coil which may be a short coil 23, at the middle portion of the secondary 95 coil, and which may be separated therefrom by a layer of insulation 24 placed on the outside of the secondary coil 20. This primary coil will be of a cylindrical form, and also have two flat portions lying over the plates 100 3 and 4.

In this use of this device the primary and secondary may be connected in the circuit in any desired manner, such as indicated at P, and S, in the diagram. The tickler coil 12 will have its extremities connected in the plate circuit of the tube, one connection being at the terminal 18, while the other connection will be through the switch that will make connection with this coil by any one 110

of the terminals 13 to 17, these taps serving to vary the effective portion of the tickler coil that is in circuit.

It will be observed that the inner coil 12 is formed of a single layer only; also the other coil 20 that crosses the coil 12 is of a single layer. The third coil is also of a single layer, and as shown is separated from the second coil by a thin layer of insulation, 10 that will bring this coil in close proximity to both of the other coils.

What I claim is:

In a radio induction circuit, a form comprising two substantially rectangular plate 15 portions, a pair of half cylinder portions joined at the ends respectively to two oppo-

site edges of said plate portions, a second pair of half cylinder portions joined at the ends respectively to the other opposite edges of the said plate portions, whereby two winding zones are provided perpendicular to each other with common intersecting portions at said plate portions, a primary and a secondary in superposed relation wound around the said form in one said zone, and a 25 tickler wound at right angles to the primary and secondary around the other said zone in close contact.

Signed at New York city, N. Y., on this 30 day of September, 1926.

MARTINUS SIEVEKING.
